UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 12,498, dated September 27, 1881.

Application filed August 17, 1881. Term of patent 3½ years.

To all whom it may concern:

Be it known that I, JULIUS PEGEL, of New York, in the county and State of New York, have invented a new and original Design for Carpets, of which the following is a specification.

This invention relates to a new and original design for carpets and similar fabrics; and it consists in the novel grouping and configuration of figures; hereinafter more fully described.

The accompanying photograph illustrates a face view of a carpet having my new design.

A, B, and C are three separate floral groups. The group C is set in a rectangular field, E, which is partly overlapped by the L-shaped border *a*, that embraces the lower part of group A. At one end of the field E is the rectangular figure D, which by cross-lines is divided into separate stripes. From the figure D extends obliquely upward the border *b*, which is beneath group A. At a right angle to the border *b* projects therefrom downwardly the oblique border *d*, which, together with the border *b* and figure D, forms the upper boundary for the group B. Above the border *d* is the angular border *e*, inclosing, with *d*, the striped field *f*. To the right of the lower part of border *d* is a

rectangular figure, F, with a diagonal central band and ornamented top and bottom lines. It abuts against the next group C. Below the group B is a large rectangle, G, having ornamental bottom stripe, *g*, castellated top *h*, and between these a series of vertical bars ornamented in heraldic fashion. The upper right-hand group, B', is represented as like group B, with the exception of a slight change in the form of the flower in the center. In the full carpet the groups B and B' may be made identically alike.

I claim—

1. The design for carpets, consisting of the figure A, substantially as shown.
2. The design for carpets, consisting of the figure B, substantially as shown.
3. The design for carpets, consisting of the figure C, substantially as shown.
4. The design for carpets, consisting of the figures A B C D E F G *a b d e f g h*, substantially as shown.

JULIUS PEGEL.
